UNITED STATES PATENT OFFICE.

JOSHUA K. CLUTTS, OF DETROIT, MICHIGAN.

BLAST FURNACE.

Application filed September 25, 1922. Serial No. 590,497.

This invention relates to blast furnaces the pipe 5^c connects through branches 5^a with and more particularly relates to blast furnaces associated with rotary kilns which latter effect a preliminary partial reduction 5 of the ore.

Among the objects of the invention are utilization of the slag heat and of the hot gases from the rotary kiln for pre-heating the air supply to the furnace and for other 10 purposes; utilization of the draw stacks of the furnace to house air pre-heating stoves; delivering partially reduced ore in measured quantities from a rotary kiln, or the like, to a blast furnace and a provision for delivering either hot or cold air or a mixture 15 thereof of regulable proportions to the furnace.

In the drawings:—

Figure 1 is a view in elevation showing 20 the complete equipment comprising the invention;

Fig. 1^a is a detail view of the charging device;

Figure 2 is an enlarged cross section on 25 line 2—2 of Figure 1;

Figure 3 is a cross section on line 3—3 of Figure 2;

Figure 4 is a detail view of a portion of the sectional air heating stove;

Figure 5 is a plan view of the complete equipment with the stacks thereof shown in section.

In these views the reference character 1 designates a blast furnace, 3 a slag car, traveling to and from said furnace, and 4 a slightly inclined rotary kiln driven by any suitable means (not shown) and having its lower or discharge end adjacent the mouth of the furnace. Raw ore is fed to the higher end of 40 the kiln 4 through a chute 5, to which such ore is delivered by any suitable means, as for example the conveyor 5^a. A gradual travel of the ore through the kiln toward the furnace 1 results from rotative actuation of 45 the kiln because of the inclination of the latter, and a sufficiently high temperature is maintained within the kiln to roast and partially reduce the ore during such travel. The heating of the kiln is effected preferably by combustion of fuel introduced, together with air under pressure into the lower end of the kiln. Thus in Figure 1, 5^b and 5^c are pipes connecting with the kiln at its lower end, the former for discharging gas, tar or 55 powdered coal and the latter furnishing air for the combustion of such fuel. Preferably

both the hot air pipe 20 and with the cold air pipe 23 so that the temperature under which the air is delivered to the kiln is regulable. 60 For charging the furnace, it is preferred to employ the device shown in Figure 1 and more fully disclosed in applicant's co-pending application, Serial Number 590,496 and filed of even date herewith. This device 65 comprises a chute 6 discharging from the stationary lower end portion 7 of the kiln, and a charging box 8 into which said chute discharges. As is best seen in Fig. 1^a, the box 8 is mounted upon the platform 8^a of 70 a weighing scale, the beam of which is indicated at 8^b. 9 is a steam or air engine actuating plungers 10 within said box for periodically ejecting the contents of the same. Preferably the top cover 11 of the furnace 75 is so connected to the forward plunger 10 as to move in unison therewith. Thus the mouth of the furnace will be uncovered at the same time that the contents of the charging box are ejected into said mouth. 80

The hot gases from the top of the furnace are delivered to a pipe 12 and are conducted thereby to two adjacent draw stacks 13, discharging into said stacks respectively through openings 14 and 14'. Within one 85 of said stacks there is disposed a boiler 15 preferably tubular while an air heating stove 16 is arranged within the other stack. Said stove, as is best shown in Figure 2, comprises separable sections through which air to be 90 heated travels tortuously upwardly. The cold air is delivered to the lower end of said stove through branches 17 from a pipe 18 leading from the blowing engine 19. From the top of said stove the heated air is taken 95 off by a pipe 20 and carried to an annular pipe 21 surrounding the lower portion of the blast furnace, there being the usual tuyère pipes 22 opening from the annulus 21 into the blast furnace. The relatively high end 100 of the kiln 4 is in communication with the stack 13, wherein the stoves are located, at a level below said stoves, so that the gaseous products of combustion discharging from the kiln are utilized to heat the stove. As a provision for mixing a regulable quantity of cold air with the supply to the furnace, a branch pipe 23 extends from the outlet end of the blowing engine 19 and connects adjacent the furnace with the hot air pipe 20, 105 the pipes 20 and 23 being respectively controlled by suitable valves 24 and 25. The 110

2
stoves 16 may be cleaned at intervals by a blast of air admitted to the lower ends of said stoves through nozzles 25^a which are connected with a pipe 25^b leading to the pipe 5 20 and supplied thereby with heated air.

The slag car 3 is adapted to travel along a suitable track 26 having branches 26' leading respectively into chambers 28 formed within the masonry base 29 of the draw 10 stacks 13. Said chambers are provided with suitable doors 30 which after introduction of a filled slag car 3 into either chamber are closed for conservation of the heat of the slag. 31 indicates flues rising through the 15 masonry base 29 respectively from the chambers 28 and discharging respectively into the draw stacks 13 at the lower ends thereof. At a suitable point above the slag chambers 28 there is mounted a tank 32 20 forming a receptacle for tar or some similar heavy hydrocarbon. 33 is a discharge pipe leading downwardly from the tank 32 and branching to discharge downwardly within each chamber 28. 34 is a steam pipe leading 25 from the boiler 15 and having a portion 35 coiled within the receptacle 32 for heating the contents thereof to liquefy the same. 36 is a pipe leading from the hot air supply main 18 and discharging downwardly into the 30 pipe 33 for placing air pressure upon the discharging tar to expedite the flow thereof.

Considering now the operation of the described apparatus, it will be understood that green or raw ore is continuously delivered 35 to the raised end of the rotary kiln 4, and owing to the rotation of said kiln in conjunction with the inclination thereof, is gradually fed from the upper to the lower end of the kiln, being subjected during this passage 40 through the kiln to the hot products of combustion rising through the kiln and thus undergoing a preliminary partial reduction. From the lower end of the kiln the ore discharges through the chute 6 into the charging box 8 from which it is periodically delivered 45 to the mouth of the furnace. The latter is continuously supplied with the necessary blast of air through the system comprising the blowing engine 19, air heating stove 16, main cold air pipe 18 and the pipes 20 and 23. The flow through the two last mentioned pipes is so regulated as to maintain for the air such a temperature as will best satisfy the operating conditions of 50 the furnace. The hot products of combustion flowing through the rotary kiln are delivered to the stacks 13 and are thus utilized for pre-heating the air in the stove 16 and also for heating the boiler 15. The hot gases 55 from the blast furnace being delivered to the stacks through the pipe 12 are similarly utilized. As a further source of heat the slag car (or cars) 3 after they are filled are conducted into one or both of the chambers 28 60 and the molten slag is subject to a discharge

of tar or the like through the pipe 33. Instantaneous combustion of the tar results owing to the high temperature of the slag and the resulting combustion products are conducted through the flues 31 to the stacks 70 13 to contribute to heating of the air stove and boiler.

The described installation, owing to the considerable employment for useful purposes of heat units which in the present 75 practice are largely wasted, is adapted to operate with high efficiency.

The employment of the rotary kiln to effect a preliminary reduction permits the employment of a blast furnace much shorter 80 than is feasible where the entire process of reduction is carried on within the blast furnace. This shorter type of furnace is advantageous in that, for a given production, a less amount of fuel is required, and also 85 the quality and composition of the iron may be more readily controlled. Thus the described furnace is peculiarly adapted to deliver iron direct to molds for making castings. 90

What I claim as my invention is:—

1. A draw stack having a base portion formed with a chamber adapted to receive a slag car and with a flue leading from said chamber to the stack, and means within 95 said stack for utilizing the heat arising from slag within said chamber.

2. The combination with a blast furnace, of a draw stack, means for delivering the hot combustion products from the furnace 100 to said stack, a track leading from the furnace into a chamber in the base of said stack, a slag car operating on said track, and means within said stack for utilizing the heat of said waste gases and that arising 105 from slag within said chamber.

3. The combination with a blast furnace, of a rotary kiln for effecting a preliminary reduction of the ore delivered to said furnace, one end of said kiln extending into 110 proximity to said furnace, a stack distant from said furnace with which the other end of said kiln communicates, means for supporting combustion in the lower portion of the kiln and means conveying the hot gases 115 from said furnace to said stack.

4. A stack having a vertical partition therein forming separate chambers for receiving heat transfer appliances, and a means for admitting combustion products to 120 said stack within each of said chambers below the level of said appliances.

5. The combination with a blast furnace having a charging opening in its top portion, of a rotary kiln for effecting a preliminary reduction of the ore delivered to 125 said furnace, and means for delivering a measured charge of ore from the kiln to the furnace.

6. The combination with a blast furnace 130

having a charging opening in its top portion, of a rotary kiln extending into proximity to said furnace, and having a discharge provision adjacent the furnace, a receptacle 5 for the discharge from said kiln, and means for intermittently delivering the contents of said receptacle to the charging opening of the furnace.

7. The combination with a blast furnace 10 having a charging opening in its top por-

tion, of a rotary kiln for effecting a preliminary reduction of the ore delivered to said furnace, a receptacle adjacent to said charging opening into which said kiln discharges, and means for weighing said receptacle with its contents and for delivering said contents to said charging opening. 15

In testimony whereof I affix my signature.

JOSHUA K. CLUTTS.
